UNITED STATES PATENT OFFICE.

WENDELL A. BARKER, OF CHICAGO, ILLINOIS.

CHUCK.

1,249,300.

Specification of Letters Patent. Patented Dec. 11, 1917.

Application filed July 29, 1916. Serial No. 112,032.

To all whom it may concern:

Be it known that I, WENDELL A. BARKER, a citizen of the United States, residing at Chicago, in the county of Cook and State of Illinois, have invented certain new and useful Improvements in Chucks, of which the following is a specification.

This invention has reference to chucks adapted to be used upon lathes and the like, and relates more particularly to the mechanism for closing the work-engaging jaws and holding them in gripping relation with the work.

One of the salient features of this invention is the provision of means whereby the chuck jaws may be readily opened and closed by the simple manipulation of a hand lever while the chuck is revolving at full speed as well as while it is standing still.

Another object of my invention is to provide simple and efficient mechanism for controlling the chuck jaws, which will simultaneously move all of the jaws an equal distance into work-engaging position and will firmly hold them in clamping relation with the work, and which will multiply a small expenditure of force exerted upon the adjusting mechanism into an extremely heavy pressure exerted upon the jaws.

To facilitate an understanding of my invention and an appreciation of its attendant advantages I have illustrated one practical and preferred embodiment thereof on the accompanying drawings, which should be considered in connection with the following description. Referring to the drawings,—

Figure 1 illustrates a longitudinal sectional view through a chuck embodying my invention;

Fig. 2 is a transverse sectional view on the line 2—2 of Fig. 1;

Fig. 3 is a similar view on the line 3—3 of Fig. 1; and Fig. 4 is a fragmentary sectional view on the line 4—4 of Fig. 1.

Referring to the drawings, reference character 5 indicates a spindle of a lathe or other machine upon which the hub 6 of a chuck-body, designated generally by reference character 7, is threaded in the usual manner, as shown in Fig. 1. In a series of radially arranged grooves 8 formed in the front face of the chuck-body are mounted a plurality, (in the present instance three) of gripping or work-holding jaws 9, the work-engaging portions 11 of which may be of any preferred construction, those shown for pur-

poses of illustration merely, being of reversible step-jaw type adapted to be reversed and adjusted to grip objects of different sizes intended to be worked. The rear face of each back portion 12 of each jaw is provided with a transversely extending groove 13 in which there is slidably disposed a pivot block 14 provided with a central bearing aperture 16 adapted to receive the trunnion 17 of a jaw-operating lever 18. Each lever is provided with oppositely extending pintles 19 and 21 which are respectively journaled in bearings formed in the front wall of the chuck-body 7 and in the back plate 22 which is pinned, bolted or otherwise rigidly secured to the rear face of the chuck-body. The pintles 19 and 21 form the fulcrums for the levers 18 about which these levers are oscillated to move the chuck-jaws in and out radially of the body, the bearing blocks 14, which are slidable transversely of the jaws, being provided for the purpose of converting the arcuate movement of the trunnion 17 into a right line movement of the chuck-jaws.

Upon the hub 6 of the chuck-body there is sleeved or rotatably mounted a member 23 which is adapted to simultaneously actuate all of the levers 18 to force the chuck-jaws into closing position. This member is provided on its periphery with three depressions 24 arranged so that they will simultaneously receive the anti-friction rollers 25 mounted upon the inturned extremities 26 of the long arms of the levers 18, as clearly shown in Fig. 3. Counterclockwise from each of these depressions 24 the member 23 is shaped to provide an elongated cam surface 27 which, when the member 23 is partially rotated in a clockwise direction relatively to the hub 6 of the chuck-body, viewing Fig. 3, swings the long arms of the levers 18 outwardly, thereby forcing the short arms inwardly to move the jaws into work-engaging position. It should be observed that upon initial movement of the member 23 the levers 18 will be moved relatively rapidly as the depressions 24 travel from beneath the rollers 25. Further movement of the levers, however, will be relatively slow because of the long gradual rise of the cam surfaces 27. The conjoint action of the long gradually rising cam surfaces and the increased leverage afforded by the levers 18 multiplies a small force applied to the member 23 into a very powerful gripping force.

exerted by the jaws upon the object or material to be held. The parts are so proportioned that the combined weight of the jaws and the short arms of the levers when multiplied by the length of the short arms is substantially equal to the combined weight of the long arms of the levers and the rollers 25 when multiplied by the effective length of the long arms, so that the jaws and the 10 levers are practically balanced and are therefore affected but little, if any, by centrifugal force when the chuck is in operation. For the purpose, however, of insuring the opening of the jaws when the cam 15 member 23 is moved to opening position as shown in Fig. 3, I provide each lever 18 with a socket 28 in which is seated a light coiled expansion spring 29 abutting at its outer end against the surrounding wall of 20 the chuck body, so that the expansive force of these springs will urge the rollers 25 into continuous engagement with the periphery of the cam member 23 thereby causing the jaws to open as the cam member is moved 25 to opening position.

Any suitable mechanism may be employed for causing the cam member 23 to rotate with the chuck body and to be partially rotated relatively to the chuck-body to close 30 or open the chuck-jaws when the chuck is rotated. I have, for purposes of illustration, shown on the drawings one practical and preferred mechanism for accomplishing this result. Referring now to Figs. 1 and 2, 35 it will be observed that the depressions 24 and cam surfaces 27 are formed at the rear end of the member 23 while the front end which projects longitudinally beyond the back plate 22 of the rotating chuck-body is 40 provided with gear-teeth 31. A gear 32 equal in peripheral circumference to the toothed portion of the member 23, and also provided with circumferential teeth 33 corresponding in number with the teeth 31, is 45 rigidly secured by a key 34 or other suitable means to the outer end of the chuck-hub 6 so as to rotate therewith.

A stationary casing comprising a circumferential wall 35, a rear wall 36, and a front wall 37 in the form of a plate rigidly secured to the forward edge of the circumferential wall 35 and having a forwardly projecting flange 38 loosely fitting within the back plate 22 of the chuck-body, is fixedly secured to the machine frame just rearwardly of the chuck-body so as to house the gears 31 and 32, as shown in Fig. 1. An annular clamping nut or ring 39 may be threaded onto the rear end of the chuck-hub 6 to prevent accidental escape of the key 34 and to assist in uniting the parts and steady- 60 ing the construction.

Within the stationary casing at the junction of the walls 35 and 36 I have fixedly 65 secured, by means of screws 41, an internal

gear 42, and laterally adjacent to said gear within the casing is mounted an internal gear 43 of equal internal diameter and provided with an equal number of gear teeth. A handle 44 extending through a slot 45 in 70 the circumferential wall 35 of the casing is fixedly secured by bolts 46 to the internal gear 43 which, by means of this handle, may be partially rotated within the casing within the limits defined by the ends 47 and 48 of 75 the slot 45. An annular ring 49 is loosely sleeved upon the hub 6 between the opposed ends of the gears 23 and 32, as shown in Fig. 1, and this ring carries on opposite faces a plurality of pairs of pinions through 80 which motion is transmitted from the gear 32 to the gear 23.

Referring to Figs. 1 and 2, it will be observed that the ring 49 carries a plurality of bearing or stud bolts 51, four being shown 85 in the present instance, upon the rear ends of which are mounted pinions 52 meshing with both the gear 32 and the internal gear 42. At their forward ends, projecting through the ring 49, these bolts are threaded 90 into bushings 53 upon which are rotatably mounted similar pinions 54, each meshing with the teeth 31 of the member 23 and with the adjustable internal gear 43.

Assuming now that the chuck is rotating, 95 the gear 32 will be rotated with the hub 6 of the chuck and by reason of the intermeshing relation of the pinions 52 with the rotating gear 32 and the stationary internal gear 42 the ring 49 will be rotated in the same 100 direction as the chuck but at a slower speed. As the ring rotates, carrying with it the pinions 54, each of which meshes with the gear teeth 31 and the internal gear 43 which normally is stationary similarly to the gear 42, the member 23 will be rotated in the same direction as the chuck and at the same speed. Since the jaw-operating levers 18 are carried by the chuck body and the member 23 is rotating in the same direction and at 105 the same speed as the chuck-body it will be manifest that no relative movement between the member 23 and the levers takes place, consequently the jaws will remain stationary 110 relatively to the chuck-body. Assuming that the parts are in the position shown in the drawings, with the chuck-jaws open and the chuck rotating in a clockwise direction, viewing Fig. 3, and a counterclockwise direction, viewing Fig. 2, should it be desirable 115 to close the jaws, the handle 44 is swung by the operator in a clockwise direction, viewing Fig. 2, carrying with it the movable internal gear 43 which, acting through the pinions 54, will impart an additional partial 120 rotation to the member 23 relatively to the chuck body and in the same direction that the body is rotating, with the result that the member 23 will travel relatively to the chuck-body in a clockwise direction, view- 125

130

- ing Fig. 3, to move the cam surfaces 27 beneath the rollers 25 and thereby, through the levers 18, force the jaws into closing position against the work in the chuck. When 5 the jaws have been tightly closed against the work by this movement of the handle 44 they will remain locked in closed position by the cam member 23 which continues to rotate with the chuck-body, there being no 10 tendency toward relative movement of this member with respect to the chuck-body by reason of the fact that the cam surfaces 27 have a very slow rise and the rollers 25 press against the cam surfaces at substantially 15 right angles to these surfaces at the point of contact. It will thus be manifest that the chuck-jaws can be closed by a simple manipulation of the handle 44 irrespective of the speed at which the chuck may be rotating. 20 When it is desired to open the jaws the handle 44 is swung in the opposite direction thereby imparting a reverse movement to the member 23 relatively to the chuck-body so as to permit the jaws to open under the 25 influence of the coil springs 29.

It is believed that my invention and its mode of operation should be readily understood from the foregoing without further description but it should also be obvious that 30 the details of construction illustrated and described are capable of wide modification and variation within the purview of the invention as defined by the following claims.

I claim:

- 35 1. In a chuck, the combination of a rotatable chuck body, jaws movable radially therein, levers pivoted on said chuck body and connected to said jaws, means concentric with said body and normally rotating 40 at the same speed and in the same direction with the latter for actuating said levers, and means for rotating said lever-actuating means relatively to said body while the latter is rotating, to effect actuation of said 45 levers.
2. In a chuck, the combination of a rotatable chuck body, jaws movable radially therein, levers pivoted on said chuck body and connected to said jaws, cam means 50 sleeved upon the hub of said body and engaging said levers, means normally effecting rotation of said cam means at the same speed and in the same direction with said body, and manually operable means for increasing or diminishing the speed of rotation of said cam means relatively to the speed of rotation of said body whereby to actuate said levers.
3. In a chuck, the combination of a rotatable chuck body, jaws movable radially 60 therein, levers pivoted on said chuck body and connected to said jaws, cam means sleeved upon the hub of said body and engaging said levers, a planetary gear transmission intermediate said hub and said cam 65 means normally effecting rotation of the latter in the same direction and at the same speed with the latter, and manually operable means acting through said planetary gear transmission to increase or diminish the 70 speed of rotation of said cam means relatively to the speed of rotation of said body whereby to actuate said levers.
4. In a chuck, the combination of a rotatable chuck body, jaws movable radially 75 therein, levers pivoted on said chuck body and connected to said jaws, a sleeve rotatably mounted on the hub of said body and formed with a plurality of cam surfaces 80 corresponding in number to said levers and each engaging one end of one of said levers, each of said cam inclines having an abrupt rise at its forward end and diminishing in 85 inclination to approximately zero at its rear end, means normally effecting rotation of said sleeve at the same speed and in the same direction with said body, and manually operable means for increasing or diminishing the speed of rotation of said sleeve relatively 90 to the speed of rotation of said body.
5. In a chuck, the combination of a body, a plurality of jaws mounted for radial movement thereon, levers mounted upon axes parallel with the axis of rotation of said body having their short arms connected with said 95 jaws, and means disposed within the chuck-body in position to act upon the long arms of said levers to force the jaws into closed position, the combined weight of the jaws and the short arms of the levers multiplied 100 by the effective length of said short arms being approximately equal to the weight of the long arms of the levers multiplied by the effective length of said long arms, whereby 105 said jaws and levers are substantially balanced within the chuck body.

WENDELL A. BARKER.
